MATTRESS VENTILATOR

Ernest Cavicchi, Arlington, Mass.

Application March 8, 1937, Serial No. 129,738

4 Claims. (Cl. 5—347)

This invention relates to ventilators and more particularly to a ventilator particularly designed for use on mattresses, pillows, upholstery and the like.

5 The object of the invention is to provide a mattress ventilator of simple and inexpensive construction capable of being quickly and securely attached to any portion of a mattress whereby to permit the free circulation of air 10 through the body of the mattress and consequently increase the effective life thereof and render the mattress thoroughly sanitary under all conditions of service.

15 A further object of the invention is to provide a mattress ventilator which may be used either with or without a retaining ring for clamping the ventilator in position on a mattress ticking, the parts being so constructed as to insure a firm positive grip on the cloth without danger of tearing, 20 ripping or otherwise damaging the fabric around said ventilator.

25 A further object is to provide a ventilator including a flat disk-like body portion having ventilating slots punched or otherwise formed therein, with the metal between the walls of the slots bent outwardly to form radial clamping tongues for direct engagement with the cloth or for co-operation with a suitable retaining ring.

30 A further object is to provide a mattress ventilator, the body of which is formed with stepped ribs disposed between the ventilating slots and which ribs not only serve to reinforce and strengthen said body but also impart a distinctive ornamental appearance to the ventilator.

35 A still further object of the invention is generally to improve this class of devices so as to increase their utility, durability and efficiency.

40 In the accompanying drawing forming a part of this specification and in which similar numerals of reference indicate corresponding parts in all the figures of the drawing:

45 Figure 1 is a perspective view of a portion of a mattress equipped with a ventilator embodying the present invention,

Figure 2 is an enlarged front elevation,

Figure 3 is a rear or inside view,

Figure 4 is a transverse sectional view taken on the line 4—4 of Figure 2,

50 Figure 5 is an enlarged transverse sectional view taken on the line 5—5 of Figure 2 showing the construction of the stepped reinforcing ribs,

55 Figure 6 is a transverse sectional view showing the retaining ring omitted and the clamping tongues in direct contact with the cloth,

Figure 7 is a plan view illustrating a modified form of the invention, and

Figure 8 is a similar view illustrating another form of the invention.

The improved ventilator forming the subject-matter of the present invention may be used on mattresses, pillows and upholstery of all kinds, and by way of illustration is shown applied to a conventional type of mattress in which 5 designates the top of the mattress and 6 one of the 10 side or end walls thereof.

The device comprises a disk-like plate or body portion 7 preferably stamped or otherwise formed from sheet metal and which may be circular in outline, as shown, said body portion being of sufficient size to entirely cover an opening 8 which is formed in the cloth or fabric 8' constituting the mattress ticking before the ventilator is applied to the mattress.

Cut, punched or otherwise formed in the body 20 portion 7 are a series of converging incisions 9 arranged in pairs with one of the incisions of each pair intersecting the other near the center of the body portion, the metal between each pair of incisions being bent to extend from the inner 25 face of the body and form tapered clamping spurs or tongues 10 and provide substantially V-shaped ventilating openings 11 through the body or plate 7. The body portion is also preferably formed with a central ventilating opening 12 30 while the marginal edge of said body is preferably scalloped or otherwise ornamented, at 13, to give the ventilator a neat attractive appearance.

Associated with the disk-like body portion 7 is a flat retaining or clamping ring 14 which coacts 35 with the inner surface of the body 5 to clamp the fabric 8' therebetween, this clamping action being effected by pressing or bending the tongues 10 into position to extend radially across the retaining ring, as best shown in Figure 4 of the 40 drawing. When the tongues 10 are clamped in engagement with the retaining ring 14, the inner faces of said tongues will be disposed parallel to the plane of the ring so that liability of the

45 terminals of the tongues cutting or tearing the mattress ticking is positively prevented. The bending of the tongues form inner shoulders 14' which bear against the inner marginal edge of the clamping ring and the adjacent fabric and materially assist in holding the ventilators in 50 position on the mattress.

Between the ventilating openings 11, the metal constituting the body 7 of the ventilator is embossed or pressed outwardly to form a series of radiating ribs 15 the side portions of which are 55

55

stepped or offset with respect to their central portions, as indicated at 16 and which ribs not only serve to reinforce and strengthen the body portion 7 but also enhance the ornamental appearance of the ventilator as a whole.

5 Any desired number of ventilators may be used and positioned at any desired place or places on the mattress in order to permit the free circulation of air therethrough.

10 In applying the ventilator to a mattress, the opening 8 is first formed in the cloth or ticking after which the body portion 7 is positioned against the outside of the mattress with the tongues passing through the opening and the 15 clamping ring bearing against the inner face cloth opposite the marginal portion of the body, after which the tongues 10 are bent into position to extend across the retaining ring 14 with the shoulders 14' in contact with the fabric and ring, respectively, thereby securely clamping the ventilator in position on the ticking, as will be readily understood.

If desired, however, the retaining or clamping ring 14 may be dispensed with, and in Figure 6 20 of the drawing I have shown a ventilator in which the cloth is clamped directly between the body portion 17 of the ventilator and the tongues 18, the construction and operation of the device being otherwise similar to that shown in Figures 1 25 to 4 inclusive of the drawing. Instead of making the disk-like body portion of the ventilator circular in outline, said body portion may be substantially rectangular in shape, as indicated at 19 in Figure 7 of the drawing, or if desired, it may 30 be of diamond formation, as indicated at 20 in Figure 8. In fact, any desired shape may be imparted to the body of the ventilator and said ventilator may be made in any distinctive design so long as the body portion of the ventilator is 35 provided with the ventilating openings and clamping tongues previously referred to.

Having thus described the invention, what is claimed as new is:

1. A mattress ventilator comprising a body 40 formed with slits spaced from each other, the

material enclosed by the slits being bent to form clamping tongues and provide spaced apart ventilating openings through the body.

2. A mattress ventilator comprising a disk-like metallic body portion having slits formed therein, the metal enclosed by the slits being bent to provide ventilating openings through the body and form clamping tongues extending from the inner face of the body at outer ends of the openings, said tongues when in a clamped position having portions extending substantially parallel to the body across the outer marginal portion thereof.

3. A mattress ventilator comprising a body portion having spaced substantially V-shaped incisions formed therein with arms of each incision converging inwardly and intersecting at their inner ends, and the metal between the arms of the incisions being bent to provide radially extending ventilating openings through the body and form clamping tongues extending from the inner face of the body at outer ends of the openings, the attached ends of said tongues being provided with abutment shoulders adapted to engage the cloth of the mattress and the free ends of said tongues being adapted to clamp the cloth against the outer peripheral portion of the body, the material between adjacent ventilating openings being embossed to form outwardly projecting radiating ribs having portions disposed in stepped relation to each other.

4. A mattress ventilator comprising a body portion of a size adapting it to fit over an opening in a mattress ticking and bear against the outer face of the ticking about the opening, a clamping ring for bearing against the inner face of the ticking opposite the marginal edge portion of the body, said body being formed with spaced slots constituting radially extending ventilating openings, and tongues extending from the inner face of the body at outer ends of said openings and having their free end portions bent to extend across said clamping ring and cause the ticking to be clamped between the ring and marginal portions of the body.

ERNEST CAVICCHI.
